UNITED STATES PATENT OFFICE

168,181

SHOE

Herbert C. Otterberg, Brockton, and Charles H. Jones, Jr., Milton, Mass., assignors to Commonwealth Shoe and Leather Company, Whitman, Mass., a corporation of Massachusetts

Application August 20, 1952, Serial No. 21,132

Term of patent 3½ years

(Cl. D7—7)

To all whom it may concern:

Be it known that we, Herbert C. Otterberg and Charles H. Jones, Jr., respectively, a citizen of the United States, residing at Brockton, Massachusetts, in the county of Plymouth and Commonwealth of Massachusetts, and a citizen of the United States residing at Milton, Massachusetts, in the county of Norfolk and Commonwealth of Massachusetts, have invented a new, original, and ornamental Design for a Shoe, of which the following is a specification, reference being had to the accompanying drawing, forming a part thereof.

Fig. 1 is a top plan view of a shoe, showing our new design, illustrating the shoe untied and with one of the front gore members partially extended.

Fig. 2 is a side elevation of the shoe, the opposite side being essentially the same in appearance as the side shown here.

We claim:

The ornamental design for a shoe, as shown and described.

HERBERT C. OTTERBERG.
CHARLES H. JONES, JR.
